UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed April 13, 1928, Serial No. 269,683. Renewed June 8, 1929.

My invention relates to a slicing machine having a rotary knife and a carriage for moving the work past the cutting edge of said knife. The particular object of my invention is to provide an improved pusher plate for use with such carriage. One object of my invention is to provide a pusher plate adaptable for use with a carriage the main extended supporting surface of which lies in a horizontal plane, although the application of my pusher plate is not intended to be limited merely to such application. Another object is to provide a pusher plate and guiding means therefor which shall have a minimum tendency to bind and which shall permit the pusher plate to be moved toward and away from the gauge plate with maximum ease and speed.

Other objects will appear from time to time in the course of the specification and claims.

I illustrate my invention more or less diagrammatically in the accompanying drawings, wherein—

Figure 1 is a rear elevation;

Figure 2 is a fragmentary top view with parts in section; and

Figure 3 is a side elevation.

Like parts are indicated by like symbols throughout the specification and drawings.

A indicates any suitable slicing machine base member having the ground engaging supports or studs A¹. B generally indicates any suitable housing member or body upwardly projecting therefrom having associated therewith a face plate B¹, normally fixed in position and a gauge plate B² which may be moved toward and away from the plane of the knife as for example by rotation of the knob B³. I do not wish to be limited to any particular means for imparting movement to the gauge plate but I have herein shown lugs B⁴ on the rear of the gauge plate, levers or arms B⁵ pivoted thereto, themselves pivoted as at B⁶, a gear B⁷ associated with one of said levers and a worm B⁸, in mesh therewith and actuated by the knob B³.

C indicates the knife, it being herein shown as recessed in its forward face as at

C¹ in order to permit the peripheral portion C² to project outwardly into and slightly beyond the planes of the face plate B¹. It will be understood that the axis of the knife, in the form herein shown, lies in a generally horizontal plane but is tilted slightly from perpendicularity to the face plate B¹, in order to throw one edge of the knife forwardly into the plane of said face plate.

D generally indicates a guide track, herein shown as cylindrical, and mounted at its ends upon the supports D¹. Beneath it is a supplemental track D² herein shown as of rectangular cross-section. D³ indicates a carriage slidable along the track D and provided with a downward extension D⁴ formed to surround the track D² and thus to prevent rotation of the carriage D³ about the track D. D⁵ is any suitable manual handle whereby the carriage may be moved along the track D.

E indicates any suitable carrying tray positioned upon the carriage D³. The tray E is herein shown as having an extended plane supporting surface E¹, lying in a horizontal plane. E² indicates an upward extension from one side of the carriage plate E and is herein shown generally at right angles to the portion E¹ and is supported upon the upward extension E³ from the carriage. There is a further extension E⁴ on which are mounted the main guiding pins E⁵ and the supplemental guiding pin E⁶ herein shown as vertically aligned, although this arrangement, while preferable, is not necessary.

G indicates the pusher plate proper having a lower edge G¹ conforming generally to the surface E¹ and a lateral edge G² conforming generally to the member E². G³ is any suitable fiber or other anti-frictional support, whereby the lower edge of the pusher plate is spaced slightly above the surface E¹ and whereby the wear and rattling of the opposed parts is reduced to a minimum. G⁴ is any suitable knob adapted for the manual actuation of the pusher plate G. G⁵ indicates a lateral extension from the pusher plate associated with which is a downward outer extension G⁶ which is provided with a main

bearing sleeve G^7 and a supplemental bearing sleeve G^8 through guiding pins E^5 and E^6 respectively. It will be observed, from Figure 3, that the distance separating the sleeves G^7 G^8 is less than the length of the sleeve G^7 . The length of the sleeve G^7 in relation to the span between the two sleeves, and thus between the two guiding members E^5 E^6 penetrating the sleeves, insures a minimum of binding, and maximum ease in moving the above described pusher plate. It will be observed that the height of the member E^2 is such as to permit the member G^5 to extend outwardly over its upper edge, the portion G^6 with its bearings G^7 G^8 depending to alignment with the guiding pins E^5 and E^6 .

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

30 In the employment of a broad extended and, in the form of the device herein shown, a horizontal support, such as the member E , it is desirable to provide guiding means for a pusher plate which shall have a minimum tendency to bind. In the pusher plate herein shown the main task of guiding the plate is taken by the main bearing sleeve G^7 in slidable relation with the guiding pin E^5 . This pin penetrates the elongated bearing member, which accurately holds the guiding plate to forward movement in parallel with the side member E^2 of the carriage. In order to prevent movement of the pusher plate in planes parallel with the cutting plane 45 I provide the supplemental bearing G^8 with the supplemental guide pin E^6 passing therethrough. Owing to the short length of the sleeve G^8 and to the short distance separating the pins E^5 and E^6 , in relation to the length of the bearing G^7 , no troublesome degree of binding can take place and the face plate moves smoothly along the guiding pins. In effect the pin E^5 and its opposed bearing G^7 are the real guiding members, while the 55 pin E^6 and its guiding bearing G^8 merely prevent rotation of the pusher plate in relation to the bearing G^7 .

It will be noted, as clearly illustrated in Figure 3, that the position, length and shape 60 of the main bearing sleeve G^7 is suitable for its use as a handle for the pusher plate and the regular handle G^4 may be eliminated. The bearing sleeve may be employed for operating the movable or slidable carriage D^3 and 65 at the same time be used for sliding the

pusher plate, and thus the carriage handle D^3 may also if desired be dispensed with.

I claim:

1. In a slicing machine having a rotary knife and means for rotating it, a carriage and means for guiding it along a path across the face of said knife, a horizontal work supporting plate associated with said carriage, a side member projecting upwardly from one side of the work supporting plate, said side member lying in a plane generally perpendicular to the cutting plane, a pusher plate, mounted upon said carriage, and guiding means therefor, including a plurality of parallel guiding pins positioned on the side of said upward projection opposite to the supporting plate.

2. In a slicing machine having a rotary knife and means for rotating it, a carriage and means for guiding the carriage along a path across the face of said knife, a generally horizontal work supporting plate associated with said carriage, a work abutment member projecting upwardly from the edge of said carriage opposite the edge which approaches the knife upon the forward movement of the carriage toward the knife and lying in a plane generally perpendicular to the cutting plane, a pusher plate, mounted upon said carriage and guiding means for said pusher plate, positioned on the side of said abutment member opposite to the supporting plate, including a pair of vertically aligned guiding pins.

3. In a slicing machine having a rotary knife and means for rotating it, a carriage and means for guiding the carriage along a path across the face of said knife, a work supporting plate on said carriage, a pusher plate manually movable toward the plane of the knife, and guiding means for said plate, positioned horizontally out of line with the axis of thrust of said plate, said guiding means including a pair of adjacent, parallel pins mounted on said carriage, and a pair of sleeves mounted on the plate, adapted to receive the pins, the plate being movable on said pins, and freely removable from the carriage.

4. In a slicing machine having a rotary knife and means for rotating it, a carriage and means for guiding it along a path across the plane of said knife, a pusher plate mounted upon said carriage and guiding means for said pusher plate positioned at the edge of said carriage remote from the knife when the carriage is at the beginning of the cutting excursion, the lower edge of said plate being spaced upwardly from the work supporting upper face of the carriage, and means associated with the edge of the pusher plate remote from the guiding means, in supporting engagement with the carriage, one end of the plate being supported by said last mentioned means, the other end of the plate being supported upon the guiding means.

5. In a slicing machine having a rotary knife and means for rotating it, a work supporting carriage and means for guiding said carriage across the face and past the cutting arc of the knife, and an upstanding work engaging flange along the edge of the carriage farthest from the knife when the carriage is at the beginning of the slicing reciprocation and a work end plate adapted to overlie said work supporting carriage and guiding means therefor including a plurality of pins mounted on said carriage, said pins being positioned on the side of said upstanding work engaging flange opposite to the side on which the work end plate is positioned, bearing means adapted for slidable engagement with said pins and a supporting connection intermediate said bearing means and said plate. 7c 75
- 10 6. In a slicing machine having a rotary knife and means for rotating it, a work supporting carriage and means for guiding said carriage across the face and past the cutting arc of the knife, and an upstanding work engaging flange along the edge of the carriage farthest from the knife when the carriage is at the beginning of the slicing reciprocation and a work end plate adapted to overlie said work supporting carriage and guiding means therefor, including a pair of vertically aligned horizontal pins on said carriage, said pins being positioned on the side of said upstanding work engaging flange opposite to the side on which the work end plate is positioned, bearing means adapted for slidable engagement with said pins and a supporting connection intermediate said bearing means and said plate. 80
- 15 7. In a slicing machine having a circular knife and means for rotating it, a carriage, and means for guiding the carriage along a path across the plane and past the cutting edge of the knife, a gauge plate and means for moving it toward and away from the cutting plane of the knife, a pusher plate mounted upon the carriage, and guiding means for the pusher plate, positioned at the edge of said carriage remote from the knife when the carriage is at the beginning of the cutting excursion, the lower edge of the plate being spaced upwardly somewhat from the work supporting upper face of the carriage, and means associated with the lower edge of the pusher plate, at a point remote from the guiding means, for maintaining a supporting and spacing engagement with the carriage, the opposite end of the pusher plate being supported by said guiding means. 85
- 20 8. In a slicing machine having a circular knife and means for rotating it, a carriage, and means for guiding the carriage along a path across the plane and past the cutting edge of the knife, a flange upwardly extending from the side of said carriage remote from the cutting edge of the knife when the carriage is at the beginning of its cutting
- 25 stroke, a gauge plate and means for moving it toward and away from the cutting plane of the knife, a pusher plate mounted upon the carriage, and guiding means for the pusher plate, positioned at the edge of said carriage remote from the knife when the carriage is at the beginning of the cutting excursion, and on the side of said flange opposite to the pusher plate, including a pin positioned below the upper edge of said flange, the lower edge of the plate being spaced upwardly somewhat from the work supporting upper face of the carriage, and means associated with the lower edge of the pusher plate, at a point remote from the guiding means, for maintaining a supporting and spacing engagement with the carriage, the opposite end of the pusher plate being supported by said guiding means. 90
- 30 9. In a slicing machine having a rotary knife and means for rotating it, a carriage and means for guiding it across the face of the knife, a pusher plate mounted on said carriage and manually movable toward and from the plane of the knife, said carriage including a generally horizontal and unobstructed work supporting member, guiding means for said pusher plate, mounted along the edge of said carriage remote from said knife when the carriage is at the beginning of the slicing excursion, a sleeve slidable along said guiding means and a connection between said sleeve and said pusher plate, said sleeve being of a length sufficient to take up the angular thrust arising from the engagement of the pusher plate with the work, and of a size convenient for its use as a handle, said sleeve being adapted to serve simultaneously as a manual handle for the reciprocation of the carriage and as a means for moving the pusher plate toward the cutting plane. 95
- 35 10. The structure of claim 9, characterized by the employment of an upstanding abutment flange along the edge of the work supporting member remote from the knife when the carriage is at the beginning of the slicing excursion, the guiding means for the pusher plate, and its slidably sleeve, being positioned exteriorly of said flange. 100
- 40 11. The structure of claim 9, characterized in that the pusher plate is held against rotation in relation to said sleeve and the connection between the sleeve and pusher plate. 105
